(57) **CLAIM**

The ornamental design for a volatile material dispenser, as shown and described.

DESCRIPTION

FIG. 1 is a top perspective view of an ornamental design for a volatile material dispenser;

FIG. 2 is a front elevational view of the volatile material dispenser of FIG. 1;

FIG. 3 is a rear elevational view of the volatile material dispenser of FIG. 1;

FIG. 4 is an elevational view of a first side of the volatile material dispenser of FIG. 1;

FIG. 5 is an elevational view of a second side of the volatile material dispenser of FIG. 1, wherein the second side is opposite the first side;

FIG. 6 is a top elevational view of the volatile material dispenser of FIG. 1; and,

FIG. 7 is a bottom elevational view of the volatile material dispenser of FIG. 1.

The broken lines in the drawings depict environmental subject matter only and form no part of the claimed design.
